POULTRY SUSPENDING FRAME FOR CHILLING SHACKLE

Horace J. De Long, Ridge Road, Gainesville, Ga.

Filed Apr. 25, 1960, Ser. No. 60,309

Term of patent 14 years

(Cl. D11—1)

Fig. 1

Fig. 1 is a perspective view of a poultry suspending frame for chilling shackle, showing my new design;

Fig. 2 is a front elevational view thereof;

Fig. 3 is a top plan view thereof with the supporting frame omitted; and

Fig. 4 is a side elevational view thereof with the supporting frame omitted.

The essential features of the design reside in the portions shown in full lines.

I claim:

The ornamental design for poultry suspending frame for chilling shackle, as shown and described.
